UNITED STATES PATENT OFFICE.

WILLIAM D. WATLING, OF CHICAGO, ILLINOIS.

COMBINATION VENDING MACHINE AND AMUSEMENT DEVICE.

Application filed June 8, 1923. Serial No. 644,158.

To all whom it may concern:

Be it known that I, WILLIAM D. WATLING, a citizen of the United States, and a resident of the city of Chicago, county of Cook, 5 and State of Illinois, have invented certain new and useful Improvements in Combination Vending Machines and Amusement Devices, of which the following is a specification.

10 My invention relates to certain novel improvements in combination vending machines and amusement devices, and has for its principal object the provision of an improved construction of this character which 15 will be highly efficient in use and economical in manufacture.

Other objects will appear hereinafter.

The invention consists in the combinations and arrangements of parts hereinafter 20 described and claimed.

The invention will be best understood by reference to the accompanying drawings forming a part of this specification, and in which,

25 Fig. 1 is a front elevational view of the invention;

Fig. 2 is a sectional view of the same taken substantially on line 2—2 of Fig. 3;

30 Fig. 3 is a rear view of the interior of the invention;

Fig. 4 is a fragmentary view taken substantially on line 4—4 of Fig. 3;

Fig. 5 is a fragmentary sectional view taken substantially on line 5—5 of Fig. 3;

35 Fig. 6 is a rear view of the interior of the invention similar to that illustrated in Fig. 3;

Fig. 7 is a fragmentary sectional view taken substantially on line 7—7 of Fig. 3; 40 and

Fig. 8 is a fragmentary sectional view taken substantially on line 8—8 of Fig. 3.

Referring to the drawings, especially to Figs. 1 and 2, 10 indicates a housing having an opening 11 formed in the front wall thereof, and closed by a metal closure 13 having a peripheral frame 14 and fixed to the frame 14 by bolts 15. The closure 13 has a sight opening 16 formed therein adjacent the top edge thereof and a sight opening 17 formed therein adjacent the bottom edge thereof. The front wall at the top edge thereof has a downwardly slanting opening 18 formed therein to snugly accommodate a coin chute 19 fixed to the front wall by screws 20 and provided with a coin

slot 21. Coins are passed through the slot 21 and received by a receptacle to be hereinafter referred to. Adjacent the bottom edge of the front wall at one corner thereof is formed an opening 22 adapted to snugly accommodate a chute 23 having a portion 24 extending at the front of the wall and a portion 25 extending at the rear of the wall and supported on a base plate 26, within the 60 housing by an angularly bent portion 27. The housing 10 also includes a rear wall 10' which is removably mounted in position and locked in closed position by suitable locking mechanism as indicated at 28 and is 70 provided with a peripheral flange 29 adapted to be mounted in recessed portions 30 formed in the bottom and side walls.

Referring to Figs. 3 and 6 there is shown a support 32 fixed to the base member 26 by 75 suitable bolts 33 and provided at its lower end with a projection 34 providing a bearing and having leg portions 35 extending in a converging direction to provide a bearing portion 36 at the top thereof. Carried by the bearing portion 34 for rotation is a shaft 37 having an end portion 37' extending through the front wall and provided with an operating handle 38. The shaft 37 is further supported by a bearing plate 39 80 fixed to the base 39' of the support 32 as at 40. The shaft 37 carries a sprocket gear 41 which is operatively connected to a sprocket gear 41' by a sprocket chain 42. The sprocket gear 41' is mounted for free 85 rotation on a stationary shaft 42' carried by the bearing portion 36. The shaft 37 further fixedly carries a disc 43 having its face nearest the inner side of the front wall covered with a paper or celluloid disc 43' 90 divided into equal sectors by radially extending lines 44 and within each of the sectors is printed or embossed or otherwise, questions such as indicated at 44'. The shaft 42' carries a disc 45 also having its face nearest the inner surface of the front wall covered by a paper or celluloid disc 45'. The disc 45' has its peripheral edge portion divided into equal sectors 46 and printed or embossed or otherwise, within the sectors are bright sayings 46' being the 100 answers to the questions printed or embossed within the sectors of the disc 43'. 105

The operation of the device so far described is such that through the sight opening 17 there is visible a number of the sectors 44', and the one manipulating the 110

device rotates the shaft 37 through the medium of the handle 38 until a question, that the operator wants answered, arrives at a point opposite the arrow indicated at 5 47. During the rotation of the shaft 37 the shaft 42' is also rotated by reason of the operative connection between the two shafts and during the rotation of the shaft 42' the sectors 46 pass along the sight opening 16 which is temporarily closed by a shutter to be hereinafter referred to and upon removal of this shutter in a manner to be hereinafter stated the sayings within the sector opposite the sight opening 16 become visible answering the question below the arrow 47. As will be hereinafter seen, this shutter is only operative to open the sight opening upon passage of a coin through the coin slot 18.

20 The combination and parts of the vending mechanism includes a coin chute 48 carried by supporting arms 48' having end portions fixed to the bearing portion 36 as at 49. The coin chute 48 has an open bottom 49' normally closed by a closure plate 50 carried by an arm 50' pivoted to the support 32 as at 51 and provided with an arm 52 carrying a weight 53 whereby the closure 50 is normally held in closed position. The arm 50' is also provided with a push arm 51' for engagement with a pin 52' carried by a member 53' pivotally carried by the support 32 as at 54 and having its pivotal movement in an anti-clockwise direction influenced by a spring member 53a. The member 53' has an open slot 54' extending into which is a stop pin 55 to serve to limit the pivotal movement of the member. A trigger arm 55' forms an integral part of the member 53' and abuts the lower end portion 56 of an arm 56' forming an integral part of the shutter carrying arm 57 carrying the shutter 57 which is adapted to close the sight opening 16. The shutter carrying arm 57' is carried by the support 32 and pivoted thereto as at 58 and has its pivotal movement in a clock-wise direction influenced by a spring member 58' having one end as at 59 fixed to the adjacent leg 37 and its opposite end fixed as at 59' to a projection 60. The arm 56' is operatively connected by means of a wire link 60' to a member 61 carried by the support 32 and pivotally connected thereto as at 61'. The member 61 at its lower end carries a wire link 62 having its free end as at 62' operatively connected to a cup 63 having an open bottom and adapted to normally rest upon a platform 63' and adapted to be shifted upon pivotal movement of the member 61 over the chute 23. When the cup 63 is in its normal position the open top thereof is directly beneath a hollow conduit 64 carried by a receptacle 64' having an in-

clined bottom leading to a funnel shaped portion 65' carrying the conduit 64. In the receptacle 64' is placed the candy or gum to be paid out through the chute 23 by means of the shiftable cup 63.

The operation of the vending mechanism so far described is such that upon depositing a coin through the coin slot 18 the coin passes into the chute 48 and descends therethrough striking the closure 50 causing the arm 50' to pivot whereby the push arm exerts force against the pin 52' and actuates the trigger arm 55' releasing the member 56' for pivotal movement. By movement of the member 56' the shutter is removed from closing position behind the sight opening 16 and the member 61 by reason of its operative connection to the member 56' is pivoted about its pivot point shifting the cup 63 over the chute 23 permitting the gum or candy to drop into this chute and pass through the opening 22 where the one operating the machine receives the gum or candy from the exterior end 24 of the chute. From the closure 50 the coin indicated at 51a drops into a receptacle 52a having a neck portion 54a located under the chute 48. When the cup 63 is swung on its pivot an extension 63a thereon prevents the articles from falling from the conduit 64.

After this operation takes place it will be apparent that means must be provided to reset the mechanism in its initial position and this is accomplished by providing a member 66 having one end indicated at 66' pivotally supported by the support 32 as at 67 and having its pivotal movement about its pivot point in an anti-clockwise direction influenced by a spring member 67' having one end as at 68 connected to the support 32 and its opposite end as at 68' connected to the opposite end of the member 66. The member 66 carries a pin 69 mounted for adjustment within a slot 69' formed in the member 66 and adapted for engagement with the arm 56' when the member 66 is pivoted in a clockwise direction. The pivotal movement of the member 66 is brought about by the provision of a pin member 70 carrying a cylindrical sleeve 70' adapted for engagement with the teeth of the sprocket gear 41'. The sleeve 70' of the pin 70 is normally held in contact with the teeth of the sprocket gear 41' by reason of the spring member 67' which has a tendency to pivot the member 66 in a direction to bring the sleeve 70' into engagement with the teeth.

The operation of the mechanism above described is such that to reset the vending mechanism and to close the shutter by rotation of the sprocket gear 41' the member 66 is pivoted in an anti-clockwise direction bearing the pin 69 on the member 56' 130

causing said member to pivot to bring its end portion 56 in abutment with the trigger arm 56'.

From the description herein and brief description of the operation of the mechanism involved it will be seen that I not only provide a vending machine but also provide a device which will be amusing and such amusement can be had at an economical cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come without the scope of the appended claims.

Having described my invention what I claim as new and desire to secure by Letters Patent, is:

1. A device of the class described including a housing having two openings therein, a rotatable disc member for each opening, arranged within the housing and having portions visible through its opening, means for manually operating said disc members, a spring-drawn shutter, a coin controlled trip device for holding the shutter against the action of its spring in position to obstruct the view of one disk member, means within the casing for actuating said trip device to allow the opening of the shutter, and means actuated upon rotation of the disc members adapted to re-engage the shutter with said trip device after each opening operation.

2. A device of the class described including a housing having sight openings formed in a wall thereof, members within the housing and having portions visible through the sight openings and operatively connected together for rotation and having their sides adjacent the sight openings covered with disc shaped members having printed matter thereon, a coin-controlled trip device, a shutter adapted to be held by said trip device in position to close one of said sight openings, means within the housing adapted to move the shutter upon

its release to open the sight opening, and means under the control of the first named members for causing the shutter to close said sight opening.

3. A device of the class described including a housing having sight openings formed in a wall thereof, members within the housing having portions visible through the sight openings and operatively connected together for rotation, a shutter adapted to close one of the sight openings, coin controlled means for effecting the release of the shutter, means for opening the shutter on its release, means actuated upon rotation of said members adapted to move the shutter to close the sight opening, a delivery chute within the housing and having a portion projecting beyond the front wall thereof, a receptacle within the housing adapted to receive a confection to be delivered through the chute, and means operable by the first named shutter moving means adapted to deliver the confection from the receptacle to the delivery chute.

4. A device of the class described including a housing having sight openings formed in a wall thereof, members within the housing and having portions visible through the sight openings and operatively connected together for rotation and having their sides adjacent the sight openings covered with disc shaped members having printed matter thereon, a coin-controlled trip device, a shutter adapted to be held by said trip device in position to close one of said sight openings, means within the housing adapted to move the shutter upon its release to open the sight opening, means operable upon rotation of the first named members adapted to move the shutter to close said sight opening, a delivery chute within the housing and having a portion projecting beyond the front wall thereof, a receptacle within the housing adapted to receive a confection to be delivered through the chute, and means under the control of the first named shutter moving means for causing the delivery of the confection from the receptacle to the delivery chute.

In testimony whereof I have signed my name to this specification.

WILLIAM D. WATLING.
